Cornelia D. Echert
his ATTORNEY

UNITED STATES PATENT OFFICE.

ROBERT SUCZEK, OF MELNIK, CZECHOSLOVAKIA, ASSIGNOR TO C. H. WHEELER MANUFACTURING COMPANY, OF PHILADELPHIA, PENNSYLVANIA, A CORPORATION OF PENNSYLVANIA.

FLUID-COMPRESSING APPARATUS.

Application filed May 8, 1920, Serial No. 379,716. Renewed March 21, 1925.

To all whom it may concern:

Be it known that I, ROBERT SUCZEK, a citizen of the United States, residing in Melnik, Czechoslovakia, have invented certain new and useful Improvements in Fluid-Compressing Apparatus, of which the following is a specification.

My invention relates to apparatus for compressing fluid in a plurality of stages by action thereon by an ejector employing elastic motive fluid, as steam, in one stage, the condensable fluid discharged by the first stage ejector being condensed, the condensate removed and the remaining fluid, as air, being acted upon in a later stage by a second ejector, the condensable component in the mixture discharged by the second ejector being condensed and separated from the compressed fluid.

My invention resides in apparatus of the character referred to wherein the condenser for the mixtures discharged from both stages is compact or unitary; both ejectors mounted upon the condenser structure; and my invention resides further in other features of structure and combination hereinafter described and claimed.

For an illustration of one of the various forms my invention may take, reference is to be had to the accompanying drawing, which is a vertical sectional view, partly in elevation, of ejector and condenser structure embodying my invention.

Referring to the drawing, E is ejector structure of any suitable type or nature, and in the example illustrated is a tubular ejector comprising the motive fluid expanding nozzles N, the tubular diffuser D and the suction chamber A having the suction port A¹ through which enters the air or other elastic fluid to be compressed, as for example, from a steam condenser or from any other chamber or region from which the air or other compressible fluid is to be withdrawn. Steam or other suitable motive fluid is supplied to the nozzles N through a pipe a controlled by a valve b and delivering into the chamber c with which the nozzles N communicate; the steam pipe a¹ communicates with the boiler or other suitable source of steam under pressure, the valve b forming communication between the pipe a¹ and the

pipe a. The ejector E is mounted upon the chest or box B of the condenser structure K, the chest B being divided by the walls or partitions d, e and f into the four chambers g, h, i and j, the ejector E discharging mixture of motive and compressed fluids into the chamber g. The chambers have as a common wall the tube sheet or plate k held between the box B and one end of the shell m of the condenser structure K. The lower end of the shell m is closed by the plate or tube sheet n, which forms a wall or closure for the lower chest or box B¹ having the partition or wall o dividing it into the chambers p and q. If suitable or desirable, there may be formed upon the chest B¹ the feet or pedestals r resting upon a suitable support, not shown.

Within the shell m are the downwardly extending plates or baffles s and t, whose lower ends are spaced from the tube sheet n; and the upwardly extending baffle or plate u whose upper end is spaced from the upper tube sheet k, these baffles or plates dividing the interior of the shell m into four passes in which are disposed four groups of preferably vertical tubes v. Each group comprises any suitable number of tubes v, only few tubes v being indicated in the drawing for the sake of clearness. The tubes v are of brass or other suitable material secured by ferrules in the tube sheets k and n. The ferrules at the upper ends of some of the tubes v are elongated to form dams to prevent entry of water or condensate; and with some of the groups of tubes are associated drain pipes w, whose upper ends are flush with the upper surface of tube sheet k, whereby water or condensate will drain through the tubes w, these latter being provided at their lower ends with seal structures x, such seal structure and the dam structure being described in my co-pending application Ser. No. 317,875.

The first group of tubes v connects the chamber g with the chamber p; the second group connects the chamber p with the chamber h; the third group connects the chamber j with the chamber q; and the fourth group connects the chamber q with the chamber i.

The aforesaid first and second groups of

tubes are those of a so-called "inter"-condenser or interstage condenser, while the aforesaid third and fourth groups are those of a so-called "after" condenser. These 5 "inter" and "after" condensers are disposed within the same condenser unit or shell C.

A pipe or other suitable passage-forming member y connects the chamber h with the 10 suction of the second stage ejector E^1 , here indicated of the type employing a radial flow nozzle with surrounding annular diffuser, the latter discharging the mixture of motive and compressed fluids into the discharge passage z , which delivers into the aforesaid chamber j , from which the mixture passes 15 into the tubes v of the third group, wherein the motive fluid is partially condensed, thence into the chamber q and thence upwardly 20 through the fourth group of tubes v , where further condensation takes place, discharging into the chamber i and thence into the pipe or conduit j^1 , which delivers into the atmosphere or into any suitable chamber or 25 region at a pressure equal to atmospheric or either greater or less than atmospheric. When, for example, the discharge is into the atmosphere or into a region at pressure higher than atmospheric, the pressure in the dis- 30 charge z from the second stage ejector is above atmospheric pressure, the pressure in the passage z being to suitable extent higher than the pressure in the passage j^1 to effect flow through the third and fourth groups 35 of tubes and pipe j^1 .

It will thus be seen that in the first and second groups of tubes there is a relatively high degree of vacuum, while in the third and fourth groups the pressure is substantially atmospheric or greater than atmospheric.

It will be noted that both the first and second stage ejectors are secured or supported directly upon the condenser unit or structure, this arrangement affording compactness and restriction of fluid paths external to the condenser to suitably small length.

Communicating with the interior of the condenser shell m is the cooling water inlet 50 c^1 , the cooling water coming first into contact with the first group of condenser tubes, passing around the lower edge of the baffle t , upwardly in contact with the tubes of the second group, over the upper edge of the 55 baffle u , then downwardly in contact with the tubes of the fourth group, around the lower end of the baffle s , upwardly in contact with the tubes of the third group, and passing outward through the condensing water 60 outlet b^1 .

Communicating with the chamber p is the condensate draw-off pipe d^1 , controlled by valve e^1 and delivering to any suitable chamber or vessel. For example, it may deliver 65 through pipe f^1 to a vacuum trap whose de-

livery side communicates with the hot well or condensate receptacle of a main or large condenser from which the ejector apparatus above described withdraws air or the like. Communicating with the chamber q is the 70 draw-off pipe g^1 controlled by a valve h^1 . When the chamber q is above or near atmospheric pressure, the pipe g^1 may deliver directly into the atmosphere or into a receptacle in which the pressure is substantially at- 75 mospheric.

As cooling liquid for the interstage condenser, water or any other suitable liquid may be employed. For example, the condensate from the main condenser from which 80 the ejector apparatus withdraws air may be introduced at c^1 as the cooling water and withdrawn at b^1 . Or the cooling water entering at c^1 and leaving at b^1 may be part of the cooling water pumped by the circulating 85 pump supplying cooling water to the main condenser.

With substantially the same pressure of motive fluid delivered to the nozzle structures of the first and second stage ejectors, 90 of the total motive fluid consumed by both stages, by preference the smaller portion is consumed in the first stage; by way of example merely, thirty per cent of the total motive steam may be employed in the first 95 stage. Furthermore, the ratio of compression of the first stage is preferably higher than the ratio of compression of the second stage. With these relations existing, it is desirable, though my invention is not limited thereto, that the extent of effective condenser or heat transfer surface for the first 100 two groups of tubes, those intervening between the first and second stage ejectors, shall or may be equal to or less than the extent of condenser or heat transfer surface of the third and fourth groups through 105 which the second stage ejector discharges.

What I claim is:

1. The combination with a plurality of 110 ejectors, of an interstage condenser comprising vertical tubes, one of said ejectors discharging through said tubes, connections from said tubes delivering to a second of said ejectors uncondensed fluid, both of said 115 ejectors secured directly upon the top of and discharging downwardly into said condenser.

2. The combination with a plurality of 120 ejectors, of condenser structure comprising groups of vertical tubes, one of said ejectors discharging into a plurality of said groups serially related, a connection to the suction of the last of said ejectors, and a plurality of said groups of tubes serially related receiving discharge from said last ejector.

3. The combination with a plurality of 125 ejectors, of condenser structure comprising groups of vertical tubes, one of said ejectors discharging into a plurality of said groups serially related, a connection to the suction 130

of the last of said ejectors, and a plurality of said groups of tubes serially related receiving discharge from said last ejector, said ejectors supported directly on the top of said condenser structure and discharging downwardly.

4. The combination with condenser structure comprising a plurality of groups of vertical condenser tubes serially connected, of 10 a plurality of ejectors mounted upon and discharging downwardly into said condenser structure.

5. The combination with a condenser structure, of two ejectors mounted above and 15 directly upon said structure, a group of vertical condenser tubes within said structure receiving the downward discharge from one of said ejectors and discharging into the other of said ejectors, a second group of vertical tubes within said structure receiving the downward discharge from said other ejector, and means for passing cooling medium into said structure in contact with said groups of tubes.

23 6. In combination, condenser structure comprising an upper chest having a pair of chambers, a group of vertical condenser tubes communicating with each of said chambers, a lower chest having a chamber 30 communicating with both of said groups of tubes, a second pair of chambers in said upper chest, a group of vertical condenser tubes communicating with each of said last named chambers, a second lower chamber in 35 said lower chest communicating with both of said last named groups of tubes, an ejector discharging into one of said first named upper chambers, a second ejector having its suction connected to the second of said first 40 named upper chambers and delivering into one of said second named upper chambers, a fluid discharge conduit communicating with the other of said second named upper chambers, and a condensate discharge conduit 45 communicating with each of said lower chambers.

7. The combination with condenser structure comprising a vertical condenser tube shell, four groups of condenser tubes in said shell, four chambers at the upper end of said shell, two chambers at the lower end of said shell, one of said groups of condenser tubes communicating with one of said upper chambers and one of said lower chambers, 55 the second of said groups of tubes communicating with said one lower chamber and with a second of said upper chambers, the third of said groups of tubes communicating with the third of said upper chambers and the second lower chamber, the fourth of said groups of tubes communicating with said second lower chamber and with the fourth of said upper chambers, an ejector discharging into said one upper chamber, a second 60 ejector having its suction connected with

said second upper chamber and discharging into said fourth upper chamber, a fluid discharge conduit communicating with said third upper chamber, and means for passing cooling water through said shell.

8. The combination with an ejector, of a condenser unit comprising a shell, end chests thereon, one of said chests having separate compartments, tubes terminating in said compartments and in a compartment in the 75 other end chest, said ejector discharging through said tubes, a second ejector having its suction connected to one of said first named compartments, a plurality of separate compartments in said one of said chests, 80 tubes connecting said compartments with a second compartment in said other of said end chests, said second ejector discharging into one of said last named compartments in said one of said end chests and through 85 said tubes into the other of said last named compartments, and independent condensate draw-offs communicating, respectively, with said compartments in said other end chest.

9. The combination with a plurality of 90 ejectors, of condenser structure comprising conduit structure delivering to the second stage ejector the discharge from the first stage ejector, separate conduit structure receiving discharge from the second stage ejector, and means for effecting heat transfer from each of said conduits to cooling medium, the condensing surface of said second named conduit being at least as great as the condensing surface of said first named conduit. 95

10. The combination with a plurality of 100 ejectors, of condenser structure comprising conduit structure delivering to the second stage ejector the discharge from the first stage ejector, separate conduit structure receiving discharge from the second stage ejector, and means for effecting heat transfer from each of said conduits to cooling medium, the condensing surface of said first 105 named conduit being less than the condensing surface of said second named conduit. 110

11. The combination with a plurality of 115 ejectors, of condenser structure comprising conduit structure delivering to the second stage ejector the discharge from the first stage ejector, separate conduit structure receiving discharge from the second stage ejector, and means for effecting heat transfer from each of said conduits to cooling medium, the condensing surface of said second named conduit being at least as great as the condensing surface of said first named conduit, the motive fluid consumption and ratio of compression of the first stage ejector being, respectively, less and greater than the steam consumption and ratio of compression of the second stage ejector. 120

12. The combination with a plurality of 130 ejectors, of condenser structure comprising

- conduit structure delivering to the second stage ejector the discharge from the first stage ejector, separate conduit structure receiving discharge from the second stage 5 ejector, and means for effecting heat transfer from each of said conduits to cooling medium, the condensing surface of said first named conduit being less than the condensing surface of said second named conduit, 10 the motive fluid consumption and ratio of compression of the first stage ejector being respectively, less and greater than the steam consumption and ratio of compression of the second stage ejector.
13. The combination with a plurality of 15 ejectors, of condenser structure comprising groups of tubes, one of said ejectors discharging into said tubes, the last of said ejectors receiving discharge from said one 20 of said ejectors and discharging into serially related groups of tubes conducting the discharge in opposite directions, and means for extracting heat from said tubes.
14. The combination with a plurality of 25 ejectors, of condenser structure comprising vertical tubes, one of said ejectors discharging into said tubes, the last of said ejectors receiving discharge from said one of said ejectors, a plurality of serially related 30 groups of vertical tubes receiving the discharge of said last ejector and conducting it in opposite directions, and means for extracting heat from said tubes.
15. The combination with a plurality of 35 ejectors employing condensable motive fluid, of inter and after surface condensers therefor, the cooling surface of an after condenser being greater than the cooling surface of an 40 inter-condenser.
16. The combination with a plurality of 45 ejectors operated by elastic motive fluid, of inter and after surface condensers therefor, the nozzle structure of an earlier stage ejector being so proportioned as to consume less motive fluid than the nozzle structure of a 50 later stage ejector, the cooling surface of an after condenser being greater than the cooling surface of an inter-condenser.
17. The combination with a plurality of 55 ejectors employing condensable motive fluid, of inter and after surface condensers therefor, the cooling surface of an after condenser being greater than the cooling surface of an inter-condenser, a common shell for said 60 inter and after condensers, and means for passing cooling medium through said shell.
18. The combination with a plurality of 65 ejectors operated by elastic motive fluid, of inter and after surface condensers therefor, the nozzle structure of an earlier stage ejector being so proportioned as to consume less motive fluid than the nozzle structure of a 70 later stage ejector, the cooling surface of an after condenser being greater than the cooling 75 surface of an inter-condenser, a common shell for said inter and after condensers, and means for passing cooling medium through said shell.
19. The combination with a plurality of 80 ejectors employing condensable motive fluid, of inter and after surface condensers therefor, the cooling surface of an after condenser being greater than the cooling surface of an inter-condenser, said inter and after condensers comprising a plurality of vertical 85 tubes through which said ejectors discharge, a shell common to said inter and after condensers, and means for passing cooling medium through said shell.
20. The combination with a plurality of 90 ejectors operated by elastic motive fluid, of inter and after surface condensers therefor, the nozzle structure of an earlier stage ejector being so proportioned as to consume less motive fluid than the nozzle structure of a 95 later stage ejector, the cooling surface of an after condenser being greater than the cooling surface of an inter-condenser, said inter and after condensers comprising a plurality of vertical 100 tubes through which said ejectors discharge, a shell common to said inter and after condensers, and means for passing cooling medium through said shell.
21. Apparatus for raising uncondensable 105 elastic fluid from a pressure corresponding to the pressure within a steam condenser to substantially atmospheric pressure, consisting of only two ejectors disposed in tandem, inter and after condensers for said ejectors, a common shell for said condensers, and means disposed at one end only of said shell for carrying off the entire condensate produced in said inter and after condensers.
22. Apparatus for raising uncondensable 110 elastic fluid from a pressure corresponding to the pressure within a steam condenser to substantially atmospheric pressure, consisting of only two ejectors disposed in tandem, inter and after condensers for said ejectors, a common shell for said condensers, and means disposed at one end only of said shell for carrying off the entire condensate produced in said inter and after condensers, the 115 cooling surface of said after condenser being greater than the cooling surface of said inter condenser.
23. Apparatus for raising uncondensable 120 elastic fluid from a pressure corresponding to the pressure within a steam condenser to substantially atmospheric pressure, consisting of only two ejectors disposed in tandem, inter and after condensers for said ejectors, a common shell for said condensers, and means for cooling said inter and after condensers by the same cooling medium.
24. Apparatus for raising uncondensable 125 elastic fluid from a pressure corresponding to the pressure within a steam condenser to substantially atmospheric pressure, con-

sisting of only two ejectors disposed in tandem, inter and after condensers for said ejectors, a common shell for said condensers, a condensate drain for the interstage condenser, and a separate condensate drain for the after condenser.

25. Apparatus for raising uncondensable elastic fluid from a pressure corresponding to the pressure within a steam condenser to 10 substantially atmospheric pressure, consisting of only two ejectors disposed in tandem, inter and after condensers for said ejectors, a common shell for said condensers, a condensate drain for the interstage condenser, a separate condensate drain for the after condenser, and a discharge outlet from 15 said after condenser independent of said second drain for discharging the compressed uncondensed fluid to substantially atmospheric pressure.

26. A combined condenser and ejector unit comprising a single condenser unit containing inter and after condensers, ejectors mounted upon said condenser unit, one 25 of said ejectors discharging into said inter-condenser, a connection from said inter-condenser to the suction of a second of said ejectors, and said second ejector discharging into said after condenser, and separate condensate draw-offs for carrying away the condensate from said inter and after condensers.

27. A combined condenser and ejector unit comprising a single condenser unit containing inter and after condensers, ejectors mounted upon said condenser unit, one of 35 said ejectors discharging into said inter-condenser, a connection from said inter-condenser to the suction of a second of said ejectors, said second ejector discharging into said after condenser, and means for drawing off the condensate from said inter-condenser independently of the condensate from said after condenser.

28. A combined condenser and ejector unit comprising a single condenser unit containing inter and after condensers, ejectors mounted upon said condenser unit, one of 45 said ejectors discharging into said inter-condenser, a connection from said inter-condenser to the suction of a second of said ejectors, said second ejector discharging into said after condenser, means for drawing off the condensate from said inter-condenser independently of the condensate from said

after condenser, and means for discharging the compressed elastic fluid from said after condenser through an independent passage.

29. The combination with a condenser shell, of inter and after condensers therein, 60 tube sheets forming end closures for said shell, a plurality of groups of tubes extending through said shell and through said sheets, an end chest on said shell divided into compartments, ejectors connected in tandem with each other and with said inter and after condensers through the compartments of said end chest, another end chest on said shell divided into independent compartments, and independent condensate draw-offs 65 communicating with said compartments.

30. The combination with a condenser shell, of inter and after condensers therein, 70 each of said condensers comprising a plurality of tubes extending through said shell, chests on opposite ends of said shells having compartments communicating with said tubes and connecting them in tandem with each other, an ejector discharging into the 75 inter-condenser, a second ejector receiving discharge from said inter-condenser and discharging into said after condenser, the condensate from all said tubes collecting in one of said end chests remote from said 80 ejector connections.

31. The combination with a condenser shell, of inter and after condensers therein, 85 each of said condensers comprising a plurality of tubes extending through said shell, 90 chests on opposite ends of said shells having compartments communicating with said tubes and connecting them in tandem with each other, an ejector discharging into the inter-condenser, a second ejector receiving 95 discharge from said inter-condenser and discharging into said after condenser, the condensate from all said tubes collecting in one of said end chests remote from said 100 ejector connections, and independent condensate draw-offs communicating with different compartments of said last named chest for conducting away the condensates of said inter and after condensers, respectively.

In testimony whereof I have hereunto affixed my signature this 6th day of May, 1920.

ROBERT SUCZEK.
